UNITED STATES PATENT OFFICE.

JAMES G. ACCLES, OF BIRMINGHAM, ENGLAND.

PISTOL SUCH AS IS USED FOR SLAUGHTERING PURPOSES.

Application filed January 28, 1920. Serial No. 354,671.

To all whom it may concern:

Be it known that I, JAMES GEORGE ACCLES, a subject of the Kingdom of Great Britain, residing at 223 Wellington Road, Perry Barr, Birmingham, in the county of Warwick, England, mechanical engineer, have invented certain new and useful Improvements in or Relating to Pistols Such as Are Used for Slaughtering Purposes, of which the following is a specification.

This invention relates to pistols such as are used for slaughtering cattle or other animals, of the type in which a captive bolt or rod is used which is impelled by the explosion of a cartridge, and which may be returned by air compressed by the bolt on its outward movement. The present invention comprises a pistol of this type having a sliding hammer adapted to co-operate with the means for retaining the barrel in the firing position. The provision for retaining the barrel in the firing position may comprise a sliding spring-controlled barrel stop catch which, upon being actuated to release the barrel, is adapted to displace the hammer into a partially cocked position. The hammer may be adapted to co-operate with a sear adapted to be actuated by a sliding trigger. The sear may be pivoted to a sliding spring-controlled sear bolt. The sear may be adapted to engage with a relatively stationary part by virtue of which the hammer is released.

A bayonet or equivalent connection may be provided between the barrel and the frame. The barrel may have a cam surface adapted to co-operate with the means for retaining the barrel in the firing position. The barrel may be furnished with a sliding ejector adapted to co-operate with a cam surface upon the frame. Releasable stop provision may be incorporated for limiting the pivotal movement of the barrel.

The handle may be hollow and contains a piston by virtue of which the barrel may be lubricated.

In order that this invention may be clearly understood and readily carried into practice, reference may be had to the appended explanatory drawings in which Fig. 1 illustrates in sectional elevation an embodiment of the present invention.

Fig. 2 is a perspective view of the same in "broken" position.

Fig. 3 is a detail rear elevation of the barrel and its connections.

In a convenient embodiment of the present invention, the barrel *a* is adapted to swivel in relation to the frame *b*, and the frame carries a spring-controlled sliding firing pin bolt *c*, the firing pin *d* of which is adapted to project from a face of the frame located at the rear of the barrel. Adjacent to, and conveniently above, the firing pin bolt is a sliding spring-controlled barrel stop catch *e* adapted to retain the barrel in the firing position by engaging in an opening *g* in the breech of the barrel. Also adjacent to the firing pin bolt and conveniently below the same is a spring-controlled sear *f* pivoted to a sliding spring-controlled sear bolt *g*. Said sear bolt is adapted to be displaced by a sliding trigger *h*. The barrel stop catch is furnished with a projection *i* or shoulder adapted to co-operate with a projection *j* or shoulder upon the firing pin bolt *c*, and the arrangement is such that when the barrel stop catch is withdrawn to release the barrel the firing pin bolt is displaced or retracted into a position in which it is retained at half cock. To provide for this the firing pin bolt is furnished with a second shoulder or projection *k* adapted to co-operate with a shoulder *l* upon the sear *f*. When, as a result of the pulling of the trigger, the sear bolt *g* and sear *f* are drawn rearwardly, the firing pin bolt *c* is accordingly also drawn rearwardly beyond its position of half cock against the resistance of its spring *m*. After these parts have thus been retracted in a suitable degree, the sear *f* is adapted to release the firing pin bolt *c*. To provide for this release action the sear is provided with an inclined surface *n* adapted to engage with a fixed pin *o*, shoulder, or surface carried by the frame. This is adapted to displace the sear about its pivot against the resistance of its spring *p* and to disengage the sear shoulder *l* from the shoulder or projection *k* upon the firing pin bolt.

The handle *p* has a horizontal groove and tongue connection with the frame, and the frame is at the rear closed by a dove-tail slide *q* which forms the resistance for the springs *r*, *m*, *s* respectively controlling the barrel stop catch, the firing pin bolt, and the sear bolt. This dove-tail slide *q* rests at its lower extremity upon the handle *p*, and said handle is retained in relation to the frame in any suitable manner, as for instance by transverse screws or pins.

The barrel is formed with a depending

undercut projection *t* adapted to fit within an aperture in the frame, which aperture is also undercut, the said projection and aperture being of forms adapted to permit of a 5 bayonet or equivalent connection between the barrel and the frame such that the barrel projection may be passed into the aperture when the barrel is inclined in relation to the length of the frame, whereas upon the barrel being oscillated into alignment with the frame the projection cannot be extracted. The barrel has at or near its rear extremity 10 a cam surface 2 adapted upon closing to automatically retract the barrel stop catch *e* so that the latter subsequently falls into engagement with the recess 8 in the rear face of the barrel with which it is adapted to co-operate.

3 is a cartridge case extractor of exactly 20 the form well known in ordinary gun manufacture, comprising a part having a segmental notch 4 which engages with the flange of the cartridge case, this segmental notch 4 being formed with an upwardly projecting portion of a sliding part 5 which is adapted 25 to move rearwardly against the resistance of a spring 6. At 7 the frame of the gun has a shoulder which engages with the fore extremity of the member 5 and thereby 30 places the latter rearwardly upon the opening of the pistol, thereby extracting the cartridge case so that it can be readily removed.

The operation of the pistol is as follows: The operator moves rearwardly the barrel 35 stop catch *e* by the thumb-bit *u* and thus enables the barrel *a* to be oscillated laterally. The cartridge is then inserted and the barrel swung into its alined position, in which process the barrel stop catch *e* slides 40 over the cam surface 2 and ultimately engages within the perforation 8, so retaining the barrel member from its firing position. This rearward movement of the barrel stop catch *e* has, by engagement of the projection *i* with the projection *j*, rearwardly displaced 45 the firing pin bolt *c* until the projection *k* thereon has engaged with the shoulder *l* upon the sear *f*.

The trigger *h* is then pulled rearwardly, 50 and the rear extremity of said trigger *h* engages with the projection upon the sear bolt *g*, displacing said sear bolt together with the sear *f* rearwardly, and thus displac-

ing in such rearward movement the firing pin bolt *c* in a further degree. This additional rearward displacement of the firing pin bolt *c* continues until the inclined surface *n* upon the sear engages with the circular stop *o*, as a result of which engagement the rear extremity of the sear is caused to descend, with the result that the shoulder *l* of the sear is disengaged from the projection *k* of the firing pin bolt *c*, so that the latter is released and is thus enabled under the impulse of its spring *m* to move forwardly and 60 percuss the cartridge. The barrel stop catch is furnished with a thumb bit *u* by which it may be released.

The handle is hollow and contains a piston *v* operated by a screw *w*, as for instance 70 from a wing nut *x* at the lower extremity of the handle. The said handle is adapted to contain lubricant and a conduit *z* is provided extending from the lubricant chamber to the interior of the barrel. By rotating 75 the wing nut the barrel may thus be lubricated.

What I claim as my invention and desire to secure by Letters Patent is:—

1. In a firearm, a stock, a barrel pivotally mounted thereon, a spring-projected catch mounted on the stock to engage and lock the barrel in firing position, a spring-projected hammer slidably mounted in the stock, a spring-projected member slidably mounted 85 in the stock, a sear carried by said member and arranged to engage the hammer, means to disengage the sear from the hammer when the latter is fully retracted, said hammer and said catch having means to cause the catch to retract the hammer to "half cocked" 90 position when the catch is disengaged from the barrel.

2. In a firearm, a stock, a barrel pivotally mounted thereon, a spring-actuated hammer 95 mounted in the stock, means to cock and release the hammer, and a catch mounted on the stock and arranged to lock the barrel in firing position, said catch and hammer having means to cause the latter, when released 100 from the barrel, to move the hammer to "half cocked" position.

In witness whereof I have hereunto set my hand.

J. G. ACCLES.
